MICROMINIATURE ELECTRONIC PLUG-IN HOUSING

Stanley S. Wulc, Rydal, Pa., assignor, by mesne assignments, to United Aircraft Corporation, a corporation of Delaware

Filed Feb. 21, 1963, Ser. No. 73,679

Term of patent 14 years

(Cl. D26—1)

FIG. 1

FIG. 2

FIG. 3

FIG. 4

FIG. 5

FIG. 1 is a front perspective view showing my new microminiature electronic plug-in housing.

FIG. 2 is a top plan view thereof.

FIG. 3 is a rear elevation thereof.

FIG. 4 is an elevational view of the side opposite that shown in FIG. 1, and

FIG. 5 is a bottom plan view thereof.

I claim:

The ornamental design for a microminiature electronic plug-in housing, as shown.
